RESILIENT SUPPORT FOR MANHOLE COVERS

William F. Born, Lakewood, and Otto H. Jobski, Cleveland, Ohio, assignors to The West Steel Casting Company, Cleveland, Ohio, a corporation.

Application December 3, 1932, Serial No. 645,558

8 Claims. (Cl. 94—34)

Our invention relates to a resilient support or cushioning device for interposition between and coacting with manhole covers or the like and their supporting frames.

5 It is well known in practice that manhole covers, catch basin gratings, or other highway or street castings or covers which are removable and which close manholes and like openings, are subjected to heavy traffic. Such traffic causes wear 10 between the cover or grating and the frame, ring or like support therefor, and results in looseness and in noise. When such covers are loose the traffic subjects them to greater stresses than when firmly held in place. It is the primary object of 15 this invention to provide a means for preventing such wear and stock and which shall thereby prevent danger of breakage of the covers, resulting noise, etc.

A more specific object of the invention is to 20 provide a resilient device which is adapted to be attached to the manhole cover or grating, preferably to be removed therewith, or which may be applied to worn covers, thereby raising them again to the original level and filling the space between 25 the cover and frame, and greatly adding to the life of such used or worn covers or gratings.

More specific objects are the provision of a 30 simple, effective means for this purpose which shall constitute molded resilient elements adapted for attachment to covers or gratings to form resilient seats therefor and to closely fit between the ring and grating, and which means will have a definite shape or body of resilient material adapted to withstand repeated compressible 35 shocks and permanently retain its shape or form.

We have found that a considerable portion of 40 the weight of the cover or grating may be omitted by simple redesigning of the rigs and flanges of the cover or grating and that the necessary safety factors may still be maintained, when the absence or freedom from shock, rocking, or shifting, is attained. Another important object, therefore, is the minimizing of the shocks due to relative movement and the resulting impact between 45 the grating and the frame or ring, which thereby permits the reduction of the weight of the steel or iron castings comprising the grating or cover.

Another specific object is to provide a simple 50 cushioning means between a manhole cover and its supporting frame in such a manner that covers of lighter weight may be used, but which by virtue of effecting frictional engagement between the cover and frame holds them in assembled 55 relation with an equal or greater effect than in

the case of heavier covers without the cushioning means.

Other specific objects are the provision of such means which will be simple, effective, durable, cheaply manufactured, easily applied, and preferably removable with the cover or supporting frame and, further, which will require minimum change in the covers or gratings from the present standard practice of constructing the same.

More specific objects are to so construct such resilient cover seating devices that they may be fitted to the perimeters of covers or frames varying in external curvature from small circular covers to flat-sided square or oblong covers or gratings.

In the forms of our invention shown in the attached drawings.

Fig. 1 is a fragmentary sectional view of one form that our invention may take.

Fig. 2 is also a fragmentary sectional view of 20 that shown in Fig. 1 along the lines 2—2.

Fig. 3 is a fragmentary plan view of that shown in Figs. 1 and 2 with a portion of the cover cut away to show a resilient support in position.

Fig. 4 is a full plan view on a more reduced 25 scale of a circular manhole cover in position showing relative positions of the resilient supports.

Fig. 5 is a view similar to Fig. 4 showing the 30 resilient supports in connection with a square or rectangular cover.

Fig. 6 is a fragmentary sectional view of another 35 form of our invention.

Fig. 7 is a partial plan view of the view in 40 Fig. 6.

Fig. 8 is a partial elevation of the view in Fig. 7. 35

Fig. 9 is still another form of our invention.

Fig. 10 is yet another form of our invention.

Fig. 11 is a plan view of the form shown in 45 Fig. 10.

Fig. 12 is a partial sectional view of another 50 form.

Fig. 13 is a partial elevation of the parts shown in Fig. 12, along the line 13—13.

Referring now to Figs. 1, 2, and 3, there is 55 shown a supporting frame or ring 10 embedded in a concrete foundation 12 and having a supporting flange 14 upon which normally rests a coacting and downwardly extending flange 16 of the cover 18. Interposed between the cover flange 16 and the supporting ring or frame 10 is shown a resilient and flexible support 20, of rubber or like material. The resilient support 20 is shown as comprising a channel shape body having upwardly extending and embracing members 22 and 24, the member 22 extending upwardly a greater 55

distance than the member 24 and sloping outwardly. The embracing members 22 and 24 are joined by a connecting portion 26. Rising from the connecting portion 26 and embraced by the 5 upwardly extending members 22 and 24 are the gripping lugs 30, which are shown, as in Fig. 2, rising at an angle from the connecting member 26 and having a U-shaped recess 32 therebetween.

In applying the resilient support to the downwardly extending flange 16 of the cover 18 the dovetail forming and gripping lugs 30 are urged 10 toward each other, as viewed in Fig. 2, then pushed into the dovetail recess 34 of the flange 16 and thereafter permitted to spring outwardly to grip 15 or hold to the sides of the dovetail recess 34. The upwardly extending members 22 and 24 embrace the sides of the downwardly extending flange 16 of the cover and the resilient unit 20 is thereby held tightly against the flange 16 and can be 20 removed only by causing the gripping lugs 30 to release their grip on the walls of the dovetail recess 34.

Where the cover 18 is large and has considerable weight, in order to readily permit removal 25 of the cover, the upwardly extending member 22 of the cushioning unit 20 may have an irregular surface as shown at 36 in Fig. 3, so as to minimize the frictional engagement between it and the adjacent surface of the ring or frame 10. Where 30 a light cover is used, it is often desirable to have this frictional engagement high, in such case the irregular surface, as indicated at 36, may be dispensed with, or if not entirely dispensed with may be reduced to where the frictional engagement 35 is sufficiently high to retain the cover in its closed position.

Any desirable number of the resilient or cushioning supports may be used with a given cover. For example, in Figs. 4 and 5, we have shown a 40 number of supports spaced equidistantly around the perimeter of a round cover and a rectangular cover. Any number of supports may be used, depending upon the particular cover to which they are applied. It will generally be found unnecessary to use supports for the full perimeter 45 of the cover and it is, of course, more economical to use as small a number as are effective. The nature of the supports are such that a relatively small number afford adequate support for most types of covers and at the same time have sufficient body to permanently withstand and absorb the continual shock to which they are subjected. It will also be obvious that the use of a large 50 number of supports without such irregular edges as are shown at 36 in Fig. 3 will increase the frictional engagement between the cover and supporting frame, thereby permitting a much lighter cover to be used and which will hold such a light cover snugly in its closed position with little or no tendency for the cover to catapult from its seated position.

Referring now to Fig. 6, we have shown another 65 form that our invention may take, wherein a resilient or flexible body 40 has molded therein a metallic securing member 42 adapted to be folded over the supporting frame 44 so as to hold the resilient body 40 in the position shown, and to 70 form a seat for the flange 46 of the cover 48. The metallic securing member 42 may be of either soft, easily bendable material, such that it may be readily bent to conform to the configuration 75 of the supporting frame 44, or it may be of spring material already formed to readily snap on the supporting frame 44.

Figs. 7 and 8 show plan and elevation views respectively of this form of our invention, and while they show the inclusion of two metallic securing members, it will be understood that any desirable number of these may be used, or that instead of using flat strips as indicated, wires or other similar elements may be used. It will also be understood that the surface of the resilient body 40 coacting with the adjacent surface 50 of the cover flange 46 may be either all entirely 10 smooth or irregular as heretofore indicated, depending upon the desired frictional engagement therebetween.

In Fig. 9 is shown yet another modification that our invention may take, in which the resilient 15 seat 52, which is of an L shape section, has projecting downwardly from the horizontal element 54 projecting lugs 56 having a recess 58 therebetween, and which lugs are adapted to be urged toward each other in order to permit entry into 20 the slot 60 past the shoulder 62 of the supporting ring or flange 54. The lugs 56 are thereafter permitted to return to their normal position, thereby forming a dovetail connection with the slot 60 and holding the resilient seat 52 securely 25 to the frame or ring 64 and providing a cushion or resilient seat for the cover in its closed position.

In Fig. 10 is shown another form of our invention. The cover flange 68 has apertures, indicated at 72, therein adapted to receive the cone 30 shaped projection 74 of the resilient seat 66, the cone shaped lugs 74 having a hollow center as indicated at 76, by virtue of which the lug may be contracted to permit entry into the aperture 72 and thereafter be released to expand to firmly 35 secure the seat 66 to the cover flange 68.

Fig. 11 is a plan view of the seat shown in Fig. 10, in which is indicated an irregular surface 76, which as heretofore indicated, may be either used 40 or dispensed with as desired.

In Figs. 12 and 13 is shown yet another form of our invention which is similar to that shown in Figs. 10 and 11, but with the exception that the resilient seat 77 has a projecting lug 78, adapted to pass through the aperture 80 of the 45 cover flange 82, which lug is preferably solid in construction and definitely fixed in shape. The projecting lug 78 has a peripheral recess 84 therearound adapted to receive therein a clasp or retaining pin 86 which acts to hold the resilient 50 seat 77 in assembled relation with the cover flange 82. It will be obvious that other forms of securing means may be readily adapted to this form of our invention and that it is not considered necessary to indicate all of such means.

From the forms of the invention which we have illustrated it will be seen that we have provided a resilient and cushioning seat or support for interposition between manhole covers or gratings and their coacting supporting frame, and that these cushions or seats are effective in reducing the wear and shock to which such manhole covers or gratings are normally subjected. It will further be apparent that such cushioning devices as we have indicated may be readily applied to new or old manhole cover constructions, and that such devices may be readily removed where so required. It will also be apparent that many modifications of our invention may be made and that such modifications are within the spirit and scope of this invention as defined by the appended claims.

Further, our invention is characterized by a resilient seat or support having a definite body 75

form which is readily attachable to manhole covers or their coating frame supports, and which may be subjected to continual and repeated shocks and after each retain its form permanently and show little wear as a result thereof. The useful life of such devices is indefinitely long because of this more or less permanent characteristic, as contrasted with the short life of such filler elements as wood blocks, asphalt, tar or other filling compounds as are sometimes used. As used hereinafter in the claims such descriptive words as "resilient support", "cushioning support", etc., refer to such a support having the characteristic of relative permanency of body or shape as heretofore described.

We claim:

1. In a manhole construction the combination with a manhole cover and a supporting frame for supporting the cover over a manhole, said cover having recesses in spaced relation in its perimeter, of a resilient support adapted to provide a cushioning body between the upright and under edges of the cover and the supporting edge of the frame, said support being provided with lugs adapted to be pressed into one of said recesses whereby the support holds to the cover.

2. As an article of manufacture, a resilient cushioning element for use in a manhole construction comprising a cover element and a frame element and serving to support the cover from the frame and to space the cover from the frame, the element comprising a body of resilient material adapted to overlie a portion of the outer peripheral surface of the cover and to project inwardly beneath the edge of the cover and an integral lug element having outwardly sloping surfaces adapted to engage a dovetail recess formed in one of the elements of the manhole construction to secure the cushioning element thereto.

3. In cushioning means for a manhole device of the type comprising a frame element and a cover element adapted to be supported on a supporting flange on said frame element, the frame element having a portion adjacent the periphery of the cover element and extending upwardly above the supporting flange, the cushioning means comprising a member constructed of resiliently compressible material and having a portion adapted to fit between the cover element and the supporting flange on said frame element and a portion adapted to fit between the periphery of the cover element and the portion of the frame element extending upwardly above the supporting flange.

4. In cushioning means for a manhole device of the type comprising a frame element and a cover element adapted to be supported on a supporting flange on said frame element, the frame element having a portion adjacent the periphery of the cover element and extending upwardly above the supporting flange, the cover element and the frame element having complementary coating surfaces, one of said elements having recesses therein adjacent said complementary coating surfaces, the cushioning means comprising a plurality of members each constructed of resilient compressible material and having a portion adapted to fit between the cover element and the supporting flange on the frame element, a portion adapted to fit between the periphery of the cover element and the portion of the frame element extending above the supporting flange thereon, and a lug adapted to extend into the re-

cess to secure said cushioning member in position.

5. In cushioning means for a manhole device of the type comprising a frame element and a cover element adapted to be supported on a supporting flange on said frame element, the frame element having a portion adjacent the periphery of the cover element and extending upwardly above the supporting flange, the cover element having a plurality of apertures therein extending radially inwardly from the periphery thereof, the cushioning means comprising a plurality of members each constructed of resilient compressible material and each having a portion adapted to fit between the cover element and the supporting flange on the frame element and a portion adapted to fit between the periphery of the cover element and the portion of the frame element extending above the supporting flange thereon, and a lug adapted to extend into an aperture in said cover element to secure said cushioning member in position.

6. In cushioning means for a manhole device of the type comprising a frame element and a cover element adapted to be supported on a supporting flange on said frame element, the frame element having a portion adjacent the periphery of the cover element and extending upwardly above the supporting flange, the cover element having a plurality of apertures therein extending radially inwardly from the periphery thereof, the cushioning means comprising a plurality of members each constructed of resilient compressible material and each having a portion adapted to fit between the cover element and the supporting flange on the frame element and a portion adapted to fit between the periphery of the cover element and the portion of the frame element extending above the supporting flange thereon, and a lug adapted to extend into an aperture in said cover element to secure said cushioning member in position, the lugs being provided with enlarged heads adapted to be contracted in size to permit passing said lugs through the apertures and to thereafter expand to secure said cushioning members to the cover element.

7. In cushioning means for a manhole device of the type comprising a frame element and a cover element adapted to be supported on a supporting flange on said frame element, the frame element having a portion adjacent the periphery of the cover element and extending upwardly above the supporting flange, the cushioning means comprising a plurality of cushioning members located at spaced intervals around the periphery of the cover element, each of said members being constructed of resiliently compressible material and having a portion adapted to fit between the cover and the supporting flange on said frame elements, and a portion adapted to fit between the periphery of the cover element and a portion of the frame element extending upwardly above the supporting flange.

8. In cushioning means for a manhole device of the type comprising a frame element and a cover element adapted to be supported on a supporting flange on said frame element, the frame element having a portion adjacent the periphery of the cover element and extending upwardly above the supporting flange, the cushioning means comprising a member constructed of resiliently compressible material and having a portion adapted to fit between the cover element and the supporting flange on said frame element and

a portion adapted to fit between the periphery of the cover element and the portion of the frame element extending upwardly above the supporting flange, said cushioning member having a metallic element imbedded therein and adapted to be bent around the inner margin of the supporting flange on the frame element and

over the top of the portion of the frame element extending upwardly above said supporting flange to secure the cushioning member in position on said frame element.
